(57) CLAIM

The ornamental design for the flat undercar light bar, as shown and described.

DESCRIPTION

FIG. 1 is a perspective view of a flat undercar light bar showing our new design, with the wires broken away at the end to indicate indeterminate length;

FIG. 2 is a left end view thereof;

FIG. 3 is a right end view thereof;

FIG. 4 is a top view thereof;

FIG. 5 is a bottom view thereof;

FIG. 6 is a left side view thereof; and

FIG. 7 is a right side view thereof.

FIGS. 8 to 14 illustrate an alternate embodiment, including details of components visible through exterior walls of the flat undercar light bar illustrated in FIGS. 1 to 7, whereas:

FIG. 8 is a detailed perspective view of the alternate embodiment;

FIG. 9 is a detailed left end view thereof;

FIG. 10 is a detailed right end view thereof;

FIG. 11 is a detailed top view thereof;

FIG. 12 is a detailed bottom view thereof;

FIG. 13 is a detailed left side view thereof; and,

FIG. 14 is a detailed right side view thereof.
